ATTORNEY.

UNITED STATES PATENT OFFICE.

ADOLPHUS D. GOODWIN, OF HARAN, VIRGINIA.

SASH HOLDER AND FASTENER.

SPECIFICATION forming part of Letters Patent No. 631,254, dated August 15, 1899.

Application filed April 25, 1899. Serial No. 714,414. (No model.)

To all whom it may concern:

Be it known that I, ADOLPHUS D. GOODWIN, a citizen of the United States, residing at Haran, in the county of Roanoke and State 5 of Virginia, have invented certain new and useful Improvements in a Combined Sash Holder and Fastener; and I do hereby declare the following to be a full, clear, and exact description of the invention, such as will enable 10 others skilled in the art to which it appertains to make and use the same.

This invention is designed to provide a combined sash fastener and holder of improved character, and more particularly to provide 15 a device of this kind which is simple in construction, sure and effective in its operation, and which can be readily applied and easily manipulated to lock the sash in closed position or to secure it in raised position at any 20 desired point.

With these objects in view the invention consists in the novel construction and combination of parts, all as hereinafter described, and pointed out in the appended claim.

25 Referring to the accompanying drawings, Figure 1 is a perspective view showing the invention applied and the sash locked in closed position, the face-plate being removed. Fig. 2 is a similar view showing the sash held 30 in partially-raised position. Fig. 3 is a vertical section through the portions of the sash and frame adjacent to the lock and holder. Fig. 4 is a front or face view with the face-plate in position, the sash being closed. Fig. 5 is 35 a detail perspective view of the operating device or lever.

Referring to the drawings, the letter A indicates a window frame or casing, and B a lower sash.

40 C designates the guide strips or beads in which the sash moves. Formed in the inner edge portion of one of the inner guide strips or beads is a notch or recess D, having the inclined walls d d', whereby it has its greatest depth 45 at an intermediate point, as shown. In the inner face of the side rail b of the sash B opposite the upper portion of the recess D (when the sash is in closed position) is a concavity B'. E designates a small ball which is placed in 50 said recess.

F is a face-plate which is secured to the lateral face of the strip C and closes the re-

cess laterally. The body portion of this plate is offset laterally from the adjacent face of the strip C to form a space G, through which 55 extends loosely an arm h of an operating device H, which conveniently consists of a small rod bent at right angles to form the arm h and having a guide at k. The lower end of said rod is provided with an eye or loop h' 60 to which is connected one end of a small spring K, (which may consist of a rubber band or a spring of any other suitable character.) The other end of the spring has a ring k, which is adapted to be slipped over a nail k' or other 65 projection on the frame or casing A, as shown in Figs. 1 and 4, when the sash is closed. In this position the spring holds the arm h against the under side of the ball, which is now seated partly in the concavity B' and 70 partly against the inclined wall d' of the recess D, and thereby securely locks the sash in closed position.

When it is desired to raise the sash, the ring k is disengaged from the pin k', which 75 immediately permits the operating device to drop by gravity to the position shown in Fig. 2, and the ball also drops to the position shown in this figure. When the ball is in this latter position, it permits the sash to be 80 freely raised, but prevents any downward movement of the latter by reason of its becoming wedged between the inclined wall d of the recess D and the adjacent face of the sash-rail b. It will be seen, therefore, that the 85 sash may be held at any desired point and that it is held in such a manner that it cannot be knocked or jarred down. When it is desired to lower the sash, the ring k is again engaged with the pin k', and the spring K at 90 once acts to raise the ball and free its wedging action. Should the ball become tightly wedged, a slightly-upward movement of the sash will release it.

It will be observed that in so far as the operator is concerned he has only to engage or disengage the ring k, the rest of the operation being entirely automatic.

I prefer to locate the ball, as shown, between the face of the sash and the guide-strip rather than between the edge of the sash and the casing, for the reason that the space in the latter case varies considerably in different windows, whereas the fit between

the sash and guide-strip is always more or less uniform. The present arrangement is also more accessible for the application of the device.

5 Having thus described my invention, what I claim as new, and desire to secure by Letters Patent, is—

The combination with the sash having the concavity, the guide-strip having the inclined wall notch or recess narrowed at its bottom portion, and the ball seated loosely in the space formed by said notch or recess, of the operating device having the bent arm

extending into the said notch or recess underneath the ball, the spring connected to the said device at one end, and means for detachably connecting the other end of said spring to the window frame or casing, substantially as specified.

In testimony whereof I affix my signature 20 in presence of two witnesses.

A. D. GOODWIN.
